UNITED STATES PATENT OFFICE.

HEINRICH FISCHER, OF NUREMBERG, GERMANY, ASSIGNOR TO H. FISCHER & CO.,
OF NUREMBERG, BAVARIA, GERMANY.

TOY LORRY.

Application filed July 3, 1924, Serial No. 723,966, and in Germany January 10, 1924.

This invention relates to a toy lorry which differs from the toys of known type in such a manner that the toy lorry is constructed as a lorry with tiltable box, said tiltable box being periodically tilted forward and backward by the clockwork which drives the lorry. Every time the box is being tilted the movement of the lorry is interrupted and the lorry continues to move only when the box has been tilted back.

The invention will be best understood from a consideration of the following detailed description taken in connection with the accompanying drawings forming a part of this specification, with the understanding that while on the drawings one embodiment of the invention is disclosed, the invention is not confined to any strict conformity with the showing of the drawings, but may be embodied in any manner which does not make a material departure from the salient features of the invention.

In the drawing:—

Fig. 1 shows the motor toy in side elevation, the rear part of the side wall being broken off in order to make the gear visible.

Fig. 2 is a side elevation of the driving gear, the lorry box being shown in tilted position.

Fig. 3 shows the driving gear in plan view.

Figs. 4 and 5, and 6 and 7 respectively show constructional details.

The toy lorry consists in the well known manner of a frame 1 with the two front running wheels 2 and the two rear driving wheels 3. On the carriage frame 1 the tiltable box 5 is tiltably mounted by means of an axle 4, the rear wall 6 of said box being adapted to be laid down and connected by means of a link 7 with the carriage frame 1 in such a manner that the rear wall opens automatically when the box is being tilted and closes automatically when the box is tilting back.

The driving gear consists in a manner known per se of a clockwork and the gear case 8 is accommodated in the carriage frame 1 above the rear driving wheels 3.

A driving gear wheel 10 is mounted on the winding-up or spring axle 9 so that it does not revolve with said axle when the same rotates in the winding-up direction but only when said axle rotates in the direction of unwinding. A pinion 11 meshes with said

gear wheel 10. A toothed wheel 12 is keyed on the axle of the pinion 11 and meshes with a pinion 14 keyed on the rear axle 13.

To the driving gear wheel 10 a cam disk 15 (Figs. 4 and 5) is rigidly connected which has a cam 16. On the driving shaft 9 a sliding piece 18 (Figs. 6 and 7) is mounted with the aid of a longitudinal slit 17 so that it can be displaced in vertical direction. The upper end 19 of this sliding piece 18 engages with the cam disk. On the bent end 19 of the sliding piece 18 an arm 20 is fixed which bears from below against the tiltable box 5, the lower end of the sliding piece 18 being hingedly connected with a bow-shaped frame 21 which is pivotally mounted in the gear case with the aid of an axle 22 and carries at its other end the rear axle 13.

The operation of the device described is as follows:—

When the driving gear runs off, after having been wound up, the driving shaft 9 revolves together with the driving gear wheel 10 and the cam disk 15 rigidly connected with said gear wheel, and the cam 16 of said cam disk acts from below upon the upper bent end 19 of the slideable piece 18 and lifts the same. The arm 20 which is lifted at the same time acts from below upon the tiltable box 5 and tilts the same, the rear wall 6 of said box opening at the same time.

When the sliding piece 18 is raised, not only the arm 20 is raised and the box 5 tilted, but the frame 21 is rotated in clockwise direction, whereby the pinion 14 of the rear axle 13 is lowered and brought out of gear with the toothed wheel 12. The driving of the rear wheels 3 of the vehicle is thus interrupted so that the vehicle stops.

When the rotation of the cam disk 15 continues the sliding piece 18 descends and also its arm 20, so that the tiltable box, owing to its weight, returns to the initial position, e. g. is tilted back. The frame 21, which carries the rear axle 13, is at the same time pivoted in anticlockwise direction and the pinion 14 of the rear axle 13 is raised and brought again in gear with the toothed wheel 12 so that the carriage continues to run. These movements are repeated periodically and produce an extraordinarily nice effect.

I claim:—

1. A toy lorry comprising in combination a lorry frame, a tiltable box on said lorry frame, means for periodically tilting said box forward and backward consisting of a 5 clockwork, a driving gear wheel driven from said clockwork, a shaft on which said driving gear wheel is mounted, a slidable piece mounted on said shaft so that it does not rotate with the same but is movable in vertical direction, an upper bent edge of said sliding piece, a cam disk rigidly connected with said driving gear wheel and designed to intermittently act upon said bent edge of said sliding piece, an arm projecting from said sliding piece and bearing from below against said tiltable box. 10
2. A toy lorry comprising in combination a lorry frame, a tiltable box on said lorry frame, a rear wall of said box hingedly fixed 20 at its lower end on said box, means for periodically tilting said box forward and backward consisting of a clockwork, a driving gear wheel driven from said clockwork, a shaft on which said driving gear wheel is mounted, a slidable piece mounted on said shaft so that it does not rotate with the same but is movable in vertical direction, an upper bent edge of said sliding piece, a cam disk rigidly connected with said driving gear 25 wheel and designed to intermittently act upon said bent edge of said sliding piece, an arm projecting from said sliding piece and bearing from below against said tiltable box, so that said box is tilted downward at the rear end if said sliding piece is raised, and a link hingedly connecting said rear wall of said box with said lorry frame so that said rear wall opens and closes when said box is tilted up and down. 30
3. A toy lorry comprising in combination a lorry frame, two front running wheels under said frame, a tiltable box on said lorry frame, a rear wall of said box hingedly fixed at its lower end on said box, means for periodically tilting said box forward and backward consisting of a clockwork, a gear case on said lorry frame, a driving gear wheel driven from said clockwork, a shaft on which said driving gear wheel is mounted, a slidable piece mounted on said shaft so that it does not rotate with the same but is movable in vertical direction, an upper bent edge of said sliding piece, a cam disk rigidly connected with said driving gear wheel and designed to intermittently act upon said bent edge of said sliding piece, an arm projecting from said sliding piece and bearing from below against said tiltable box so that said box is tilted downward at the rear end if said sliding piece is raised, a link hingedly connecting said rear wall of said box with said lorry frame so that said rear wall opens and closes when said box is tilted up and down, a bow-shaped frame hingedly connected with the lower end of said sliding piece, an axle in said gear case on which axle said sliding piece is pivotally mounted, a rear axle of said lorry frame mounted in the rear end of said bow-shaped frame, two driving wheels for the vehicle on said rear axle, a pinion on said rear axle, an intermediate axle journalled in said gear, a pinion on said intermediate axle and meshing with said driving gear wheel, and a toothed wheel keyed on said intermediate axle and designed to mesh with said pinion on said rear axle when said bow-shaped frame is in the normal position the connection between said driving clockwork and said rear wheel axle being interrupted when said bow shaped frame is oscillated in downward direction by said sliding element being raised to tilt the box so that the pinion on said rear axle is disengaged from said toothed wheel on the intermediate axle and the vehicle is stopped. 40 45 50 55 60 65 70 75 80 85

In testimony whereof I affix my signature.
HEINRICH FISCHER.
